UNITED STATES PATENT OFFICE.

THOMAS REED HACKWORTH, OF RICHARD CITY, TENNESSEE.

ROOFING.

1,052,245.

Specification of Letters Patent.

Patented Feb. 4, 1913.

Application filed December 28, 1911, Serial No. 668,320. Renewed August 24, 1912. Serial No. 716,880.

To all whom it may concern:

Be it known that I, THOMAS R. HACKWORTH, a citizen of the United States, residing at Richard City, in the county of Marion 5 and State of Tennessee, have invented a new and useful Roofing, of which the following is a specification.

The present invention aims to provide a roof covering of novel and improved form, 10 the covering consisting of a series of tiles formed in place upon the roof, means being provided for holding the tiles upon the roof, which means constitutes a part of the molding structure in which the tiles are fastened.

A further object of the invention is to provide a means for yieldingly separating superposed layers of tiles in a roof, the said means consisting of a sheet of flexible material, preferably water-proof, one end of the sheet being interposed between the overlapping ends of successive layers of tiles, the other end of the sheet overlapping the exposed ends of one layer of tiles, the construction being such that the last named end of the sheet of material constitutes a temporary covering for the tiles, which covering may be severed, after the tiles are in place.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawing,—Figure 1 40 shows in top plan, a roof constructed in accordance with the present invention, parts being broken away; Fig. 2 is a section upon the line 2—2 of Fig. 1; Fig. 3 is a perspective showing the primary and secondary bars and the separating plates; Fig. 4 is a perspective showing a modified form of separating plate; and Fig. 5 is a perspective showing a modified form of secondary bar.

In the accompanying drawings, the number 50 1 indicates the foundation which, ordinarily, is fashioned from the boards of the roof. An angle member 2 extends along the side edges of the roof, and another angle member 3 extends along the eaves. The flanges 4 of the angle members 2 and 3 are

attached to the foundation 1, the flanges 5 of the angle members 2 and 3 upstanding, to retain in place upon the roof, the covering structure hereinafter described.

Secured to the foundation 1, and preferably in parallel relation, and disposed ordinarily at right angles to the direction in which the roof slants, are a series of primary bars 6. The separating plates 7 are provided, the same being, as shown in Fig. 3, of 60 tapered form. The narrower ends of the separating plates 7 are disposed in abutment with one of the primary bars 6, the wider ends of the separating plates 7 protruding beyond the next adjoining primary bar. The 70 secondary bars 12 alternate with the primary bars 6, the bars 12 and 6 being preferably disposed in parallel relation. Each of the secondary bars 12 connects one set of separating plates 7, the bars resting upon the 75 upper edges of the next adjoining set of separating plates 7. If desired, the separating plates 7 may be connected with the foundation 1 by means of securing elements 22. The wider ends of the separating plates 7 80 protrude beyond that secondary bar 12 whereby they are upheld, and interlocking elements are provided, for holding the separating plates 7 assembled with the secondary bar 12. These interlocking elements may 85 consist of notches 14 in the lower edges of the wider ends of the separating plates 7, which notches 14 are adapted to interlock with notches 15, formed in the upper edges of the secondary bars 12. The plastic material, preferably concrete or the like, denoted by the numeral 8, is interposed in the rectangles formed by the bars 6 and 12, and by the separating plates 7. Noting particularly Fig. 2, it will be observed that each 90 layer of plastic material 8, overlaps the next layer 9 below it, in the common and well known manner. Interposed between successive layers of plastic material is a layer of 95 yielding, water-proof material, which may be heavy paper, felt or the like, denoted specifically by the numeral 9. One end 10 of the layer 9 lies between successive layers 8 of plastic material, the other end 11 of each layer of flexible material protruding beyond one layer of plastic material and overhanging the next layer of plastic material, to serve as a covering therefor. After the plastic material 8 has set sufficiently, its end 11

100 may be cut off or severed otherwise. The 105 flanges 4 of the angle members 2 and 3 are 110

tiles which are formed by the plastic material, between the elements 12, 7 and 6, may be retained upon the foundation 1, by means of securing elements 21, preferably spikes or the like, entering the foundation 1.

If desired, the secondary bars and the separating plates may be fashioned from metal. Under such circumstances, the secondary bars, denoted specifically by the numeral 16, 10 may be equipped with key-hole slots 18. The separating plates are denoted by the numeral 17, and each separating plate terminates in a head 19, adapted to pass through the constricted portions of the slots 18, heads 19 being connected with the body portions of the plates 17, by reduced necks 20, adapted to rotate in the enlarged portion of the key-hole slot 18. The heads 19 may be inserted through the restricted portion 20 of the slot 18, whereupon, if the plate 17 be rotated, until the head 19 stands at right angles to the constricted portions of the slots 18, an effective lock will be formed, holding the separating plates 17 interengaged with the secondary bars 15.

The primary bars 6 represent the thickness of the thinner ends of the tiles which are formed between the elements 7, 16 and 12. The wider ends of separating plates 7 30 represent the extreme thickness of the thicker ends of the tiles.

Owing to the fact that the layer 9 of yieldable, water-proof material is employed, one layer of tiles will be prevented from cohering with the next layer of tiles, to form 35 a monolithic structure. Owing to the water-proof nature of the material 9, the moisture will not be absorbed out of the tiles, it, of course, being understood that the tiles 40 are formed upon the roof, in plastic condition. The layer 9 of yieldable material constitutes a cushion between successive series of tiles, so that if the tiles are trodden upon, or strained, due to wind-stress, a 45 breaking of the roof covering will be avoided.

It is to be noted that the separating plates 7 of one series, break joints with the separating plates of the next series, and thus 50 leakage between adjoining tiles is reduced to a minimum. The layer 9 of water-proof material covers the entire space between the bars 6 and 12, and by this means, leakage is further prevented.

55 That end 11 of the layer 9 which protrudes beyond the bar 12, overhangs the exposed portions of the tiles, and serves to protect the tiles from the sun, during the time that the concrete is setting. The moisture 60 is thereby retained in the tiles, and the tiles are prevented from injury, arising from any other source. This protruding end 11 may be cut away, after the tiles have acquired a sufficient set.

65 It will be understood readily that the an-

gle members 2 and 3 serve to define the margin of roof covering, as clearly shown in Fig. 1.

Having thus described the invention, what is claimed is:—

1. A roof comprising a foundation; primary bars applied to the foundation; separate series of separating plates, the plates of each series abutting against one primary bar and extending across the next primary 70 bar; separate sets of secondary bars alternating with the primary bars, the secondary bars of each set connecting the plates of one series and resting upon the plates of the next series; and overlapped layers of plastic 75 material interposed between the bars and the plates.

2. A roof comprising a foundation; primary bars applied to the foundation; separate series of separate plates, the plates of each series abutting against one primary bar and extending across the next primary bar; separate sets of secondary bars alternating with the primary bars, the secondary bars of each set connecting the plates of one series and resting upon the plates of the next series; and overlapped layers of plastic 80 material interposed between the bars and the plates, the secondary bars being of greater 85 height than the primary bars, and the separating plates being tapered, the narrower ends of the separating plates being disposed adjacent the primary bars, and the wider ends of the separating plates being disposed 90 adjacent the secondary bars.

3. A roof comprising a foundation; primary bars applied to the foundation; separate series of separating plates, the plates of each series abutting against one primary bar and extending across the next primary 95 bar; separate sets of secondary bars alternating with the primary bars, the secondary bars of each set connecting the plates of one series and resting upon the plates of the next series; and overlapped layers of plastic 100 material interposed between the bars and the plates; the secondary bars being of greater height than the primary bars, the separating plates being of tapered form, and having their narrower ends disposed adjacent the primary bars, the wider ends of the separating plates extending beyond the secondary bars, the plates and the secondary bars being 105 equipped with interlocking elements.

4. A roof comprising a foundation; primary bars applied to the foundation; separate series of separate plates, the plates of each series abutting against one primary bar and extending across the next primary bar; separate sets of secondary bars alternating with the primary bars, the secondary bars of each set connecting the plates of one series and resting upon the plates of the next series; and overlapped layers of plastic 115 material interposed between the bars and the plates.

the plates; and a layer of yieldable, water-proof material interposed between the layers of plastic material.

5. A roof comprising a foundation; primary bars applied to the foundation; separate series of separating plates, the plates of each series abutting against one primary bar and extending across the next primary bar; separate sets of secondary bars alternating with the primary bars, the secondary bars of each set connecting the plates of one series and resting upon the plates of the next series; and overlapped layers of plastic material interposed between the bars and the plates; and a layer of yieldable, water-proof material interposed between the layers of plastic material, the layer of water-proof material having a separable end overlapping the exposed portion of one layer of plastic material, and constituting a temporary covering therefor.

6. A roof comprising a foundation; primary bars applied to the foundation; separate series of separating plates, the plates of each series abutting against one primary bar and extending across the next primary bar; separate sets of secondary bars alternating with the primary bars, the secondary bars of each set connecting the plates of one series and resting upon the plates of the next series; and overlapped layers of plastic material interposed between the bars and the plates; the secondary bars being of greater height than the primary bars, and the separating plates being of tapered form, the

narrower ends of the separating plates being disposed adjacent the primary bars, and the wider ends of the separating plates extending beyond the secondary bars, the plates and the secondary bars being provided with interlocking elements; and a layer of yieldable, water-proof material interposed between the layers of plastic material, the layer of yieldable material having a severable end overhanging the exposed portion of one layer of plastic material, and constituting a removable covering therefor.

7. A roof comprising a foundation; angle members applied around the periphery of the foundation; spaced primary and secondary bars overlapping one flange of the angle members; separating plates abutting against the primary bars and overhanging the secondary bars, there being interengaging elements upon the secondary bars and the plates; means for securing the separating plates to the foundation, to hold the separating plates and the secondary bar against movement; the other flanges of the angle members constituting means for preventing the primary bars from moving longitudinally; and a plastic material interposed between the bars and the plates.

In testimony that I claim the foregoing as my own, I have hereto affixed my signature in the presence of two witnesses.
